UNITED STATES PATENT OFFICE.

GUSTAF W. HANSON, OF WICHITA, KANSAS.

DRILLING-TOOL.

1,375,093.

Specification of Letters Patent. Patented Apr. 19, 1921.

Application filed July 24, 1920. Serial No. 398,785.

To all whom it may concern:

Be it known that I, GUSTAF W. HANSON, a citizen of the United States, residing at Wichita, county of Sedgwick, and State of Kansas, have invented certain new and useful Improvements in Drilling-Tools, of which the following is a full, clear, and exact description.

The invention is designed as an underreamer, for drilling oil wells, and for similar earth boring operations in connection with either a new or standard rotary drilling mechanism.

By the utilization of the device of my invention the diameter of the hole previously cut by the drill at the end of the tool is enlarged sufficiently to accommodate the pipe sections, and their couplings, as the oil well casing descends with the progressive work of the drilling tool.

The invention consists in certain novel combinations and arrangements of parts, whereby the reaming knife blades or cutters are automatically projected laterally of the drill shank to operative position when the drilling tool reaches its working position, and are thus retained and locked for the proper performance of their functions. The projected cutters may with equal facility be positively unlocked and withdrawn, or retracted to inoperative position within the drill shank by the initial movement of the withdrawal of the drilling tool from the well hole, when required, thus permitting the tool to be lifted from the well.

Because of the arrangement of the underreaming cutters and their positively actuated projection to and withdrawal from operative position prior to the withdrawal of the tool from the well, the dangers incident to lodging of the apparatus in the well hole are avoided. The tool may readily be removed through the well casing, and replaced with convenience and despatch without the necessity of the long operation of pulling the casing section by section in the event that the tool lodges in its expanded position below the casing.

Other meritorious features and advantages will appear upon reference to the accompanying drawings and specifications in which I have described and illustrated one complete example of the physical embodiment of my invention constructed and arranged according to the best mode I have

thus far devised for the practical application of the principles of my invention.

Figure 1 is a view partly in section of a drilling tool constructed according to the invention.

Fig. 2 is a vertical sectional view of the tool in Fig. 1, looking from the right.

Fig. 3 is a bottom view of the tool.

Fig. 4 is a view showing the well casing in section with the drilling tool descending to operative position.

Fig. 5 is a view similar to Fig. 4 with the tool in operative position.

In the preferred form of the invention I attach at the lower end of the bit stem 1, a hollow shank 2, threaded at 3, and fashioned in the form of a cylindrical cast steel sleeve providing a chamber 4 for the tool mandrel 5 within the interior bore of the shank.

The mandrel is movable within limits in the shank, and is retained therein by means of a transversely disposed case hardened steel key 6, passed through openings in the wall of the shank and secured therein by a pin 8. This key also passes through the longitudinal guide slots 8' of the mandrel and permits relative movement of the shank and mandrel.

At its lower end the cylindrical mandrel is fashioned with an enlarged head 9, within which a fish-tail drilling bit 10 is secured. The pair of transversely extending bolts 11, used for this purpose hold the bit firmly in place for performing its functions of drilling the smaller bore of the well as the drilling tool descends.

The upper face of the head is fashioned with a tapered ring 12 to form a socket or seat for a complementary beveled lower edge 13 of the shank 2, and these beveled faces 12 and 13 provide for centering and retaining the shank and mandrel head with a close joint therebetween when the tool is in working position. Preferably locking lugs or clutch jaws 12' and recesses 13' are provided on the adjoining ends or edges of the shank and head to lock these parts together when in operative position, to receive and transmit the strain of the rotary movement between the shank and mandrel.

For underreaming the pipe or enlarging the well hole beneath the shoe S of the well casing, I employ a pair of reaming cutters 14 and 15 designed to cut the walls of the well hole drilled by the preceding bit 10, to

permit the descent of the well casing 16 and its couplings.

In Fig. 2 these reaming cutters are clearly shown, and each composed of a flat cast steel blade of proper thickness and provided with a lower perforated pivot-head 17. Disposed above this head is an angular slot comprising the vertical way 18 and an obliquely extending way 19, the latter projected at an angle into the blade in a plane parallel with the oblique cutting edge 20 of the blade. This cutting edge 20 is designed to cut or ream the side wall of the hole, and the vertically disposed cutting edge 21 of the blade, located at an angle to the cutting edge 20, is provided for lateral reaming or drilling of the hole.

Each reaming blade, at its upper edge 22, has a beveled corner 22', and a recess 23, one 20 of the walls 24 of the recess being beveled for a purpose to be described.

These reaming blades are each pivoted in and carried by the hollow mandrel, on a common pivot 25 or bolt, passed through the 25 spacing sleeve 25' in the mandrel head and transversely through the two pivot heads of the blades. The cutters are thus centrally disposed on the vertical axis of the mandrel and drill tool, and their cutting 30 blades are adapted to swing laterally through the respective slots 26 and 27 of the mandrel and shank.

The lower end walls of the two pairs of slots are beveled at 28 and 29, their faces 35 declining inwardly, and the beveled faces 28, when the tool is in working position, form seats for the edges 30 of the reaming blades, which are cut at approximately an angle of 45 degrees.

40 The slots of the inner member or mandrel are of approximately the same length as those of the shank, and the upper end walls of the shank slots are provided with beveled faces 31 complementary to the edges 45 24 of the locking notches 23 of the reaming blades.

For projecting and retracting the reaming blades I utilize the action of the relative movement of the mandrel and shank, 50 through the instrumentality of a cross pin or bolt 32 securely fixed in the walls of the shank and passed through opposed slots 33, 33, in the mandrel. The bolt is also passed through the slots in the reaming cutters, and when the tool is in operative position with the blades projected, the pin occupies a position in the vertical ways 18 of the slots in the blades.

Water openings 2' are provided in the 60 shank, and openings 5' in the mandrel are used for circulation of water in the drilling tool. And grooves or channels 9' are also provided in the head to permit draining of water therethrough.

65 While the tool is being lowered into the

well the reaming cutters are in retracted position within the mandrel and shank, as in Fig. 4 with the mandrel suspended at its low position, and the mandrel head hanging below the beveled clutch edge of the 70 shank. As the bit 10 strikes the ground, the movement of the mandrel is halted, but a continued, limited movement of the shank results, and this continued movement of the shank is instrumental in causing the projection of the reaming blades or cutters to 75 operative position.

Before the reaming cutters are projected, the actuating bolt 32 occupies a position near the upper ends of the angular ways 80 19 of the slots. As the shank continues its descent, the pin passes down through the slots or ways 19, positively forcing the blades to swing outwardly on their common pivot bolt 25, until the pin 32 occupies the 85 vertical ways 18 of the slots. As the blades pass through the slots 26 and 27, the beveled edges 31 of the shank slide over the complementary edges 22' until the notches 23 reach the edges 31 of the shank. The descending edges of the shank now slip into the notches and the blades are thus locked in projected position, with the notched 90 blade bearing against the periphery of the shank while drilling, to receive the inward 95 thrust of the drilling action of the blade.

The strain of work on the blades is taken up by the walls of the shank slots against which the blades are held and the lever action on the blades as the tool rotates, is 100 between the cutting edges of the blade and the contact face between the blade and walls of the slots in the shank and mandrel.

The blades are released and unlocked, and retracted by the initial movement of the 105 shank when the tool is lifted. Thus, when the tool is elevated, the shank is given an initial lift before the mandrel is moved. The locking wall 31 at the top of the slot 27 is first lifted from the notch 23 and the 110 lower end wall of slot 27 then engages the inclined edges 30 of the blades. The pin or bolt 32 is lifted into the angular portion of the ways 19. The mandrel is stationary, and the continued lift of the shank causes 115 the pin 32 to ride up in the angular slots of the blade to retract or draw in the released reamer blades. During this movement the key 6 slides through its slot 8 and the bolt 32 slides upwardly, through the 120 guide slots 33 until the key reaches the upper end of the slots. The weight of the mandrel is then taken up by the key, and the mandrel, head and fish tail bit are lifted with the shank.

Claims—

1. The combination with a slotted inclosing tool-shank, of a complementarily slotted mandrel, a transverse key in the shank in guide slots of the mandrel, a pair of ream-

- ing blades pivoted in the mandrel and adapted to be projected through the complementary slots, and means on the blades co-acting with the slotted shank for locking 5 said blades in projected position.
2. The combination with a hollow mandrel and inclosing, relatively movable tool shank, of a pair of reamer blades pivoted in the mandrel and adapted to be projected 10 through complementary slots in the mandrel and shank, a locking notch in each blade and a locking member formed as the top wall of the shank slots to engage said notches and lock the blades in projected 15 position.
3. The combination in a drilling tool, of an inner, hollow mandrel and inclosing shank, an enlarged bit head on the mandrel below the shank having an inwardly beveled 20 upper jaw, a complementary beveled jaw formed on the lower edge of the shank, and a bit fixed in said head.
4. The combination with a hollow mandrel and relatively movable inclosing shank, 25 a pair of reamer blades pivoted in the mandrel and adapted to be projected through complementary slots in the shank and mandrel by action of the shank, means for locking the blades in projected position, an enlarged bit-head on the mandrel below the shank formed with an inwardly beveled 30 upper jaw, a complementary jaw on the lower edge of the shank, and a bit fixed in said head.
- 35 5. The combination of an interior hollow mandrel and relatively movable inclosing
- shank, a pair of reamer blades pivoted in the mandrel and adapted to be projected through complementary slots in the shank and mandrel by the action of the shank, a 40 locking notch in the blade and a locking member formed at the top wall of the shank slots to engage said notches and lock the blades in projected position, an enlarged bit head on the mandrel below the shank 45 formed with an inwardly beveled upper jaw, a complementary jaw on the lower edge of the shank, and a bit fixed in the head.
6. The combination of a hollow mandrel and an inclosing relatively movable tool-shank, a pair of reamer blades pivoted in the mandrel and adapted to be projected through complementary slots in the mandrel and shank, means for locking the blades in projected position, an enlarged bit head 50 on the mandrel below the shank and a bit carried thereby, and complementary locking plugs and recesses on the adjoining edges of the shank and bit head for locking the shank and mandrel for joint rotary move- 55 ment.
7. The combination of a hollow mandrel and inclosing relatively movable tool-shank, a pair of reamer blades pivoted in the mandrel having angular slots, a fixed transverse 60 actuating pin in the shank passed through said slots for projecting said blades through slots in the mandrel and shank, and means on the shank co-acting with said blades for locking them in projected position.

GUSTAF W. HANSON.
